UNITED STATES PATENT OFFICE.

ROBERT F. GILLIN, OF NEW YORK, N. Y.

FLUSHING-VALVE.

SPECIFICATION forming part of Letters Patent No. 750,763, dated January 26, 1904.

Application filed January 29, 1903. Serial No. 140,986. (No model.)

To all whom it may concern:

Be it known that I, ROBERT F. GILLIN, a citizen of the United States, residing in the city of New York, borough of Brooklyn, in the county of Kings and State of New York, have invented a certain new and useful Improvement in Flushing-Valves, of which the following is a specification.

The invention relates to valves for controlling the flow of flushing-water to urinals; and the object of the invention is to provide a valve which shall be simply and cheaply constructed, easily attached to the urinal-bowl, and which shall be efficient and economical in operation.

The invention consists in certain details of construction and novel arrangements of parts by which the above objects are attained, to be hereinafter described.

The accompanying drawings form a part of this specification and show the invention as I have carried it out.

Figure 1 is a face view of the upper portion of a urinal-bowl equipped with my invention; Fig. 2 is a corresponding side view, partly in elevation. The remaining figures are on a larger scale. Fig. 3 is a vertical section through the valve and a portion of the urinal-bowl, the plane of section being indicated by the line 3 3 in Fig. 1. Fig. 4 is a face view showing a modification; and Fig. 5 is a corresponding vertical section, partly in side elevation.

Similar letters of reference indicate like parts in all the figures.

Referring to Figs. 1, 2, and 3, A is the urinal-bowl, of earthenware, as usual, and of any approved type, having the nipple A', projecting from its upper surface, adapted to receive and distribute the water admitted for cleansing the bowl.

B is a shell, preferably a hollow cylindrical metal casting, having a downwardly-projecting bell B', adapted to loosely inclose the nipple A' and be firmly joined thereto by cement. The shell B has an opening at each end of less diameter than the interior and is provided at one end with a flange B'', adapted to apply against the wall.

Mounted concentrically in the bell is a tube

B'', matching within the nipple and aiding to increase the strength of the connection and also to prevent the entrance of cement into the passage through the nipple.

C is the body of the valve-casing, of less diameter than the interior of the shell and extending axially therethrough, the outer end bearing a flange C' and the inner end screw-threaded to receive a flanged thimble D, having a screw-threaded extension D'', adapted to join the service-pipe M, bringing water under pressure from the street main or other source. (Not shown.) The joint between the casing and the shell, at each end of the latter, is made water-tight by gaskets E E', the former lying between the flange C' and outer face of the shell and the latter between the inner face and the flange D' on the thimble D and compressed by screwing the thimble upon the casing until sufficiently tight contact is insured.

Within the casing, near the inner end, is a diaphragm C'', having a central opening surrounded on the rear face by an annular valve-seat C', against which on the pressure side lies a packed disk or valve F, fastened by a screw F' to the end of a valve-stem F'', extending through the casing axially thereof and having a cone F'', serving as a reinforce to receive the screw F' and also to gradually reduce the area of the opening through the valve-seat as the valve approaches the latter in the act of closing.

C' is an extension of the casing beyond the flange C', screw-threaded interiorly to receive a hollow screw-plug G, the interior of which is smoothly finished to serve as a cylinder or dash-pot for a cup-leather piston F' on the valve-stem F'', the function of which is to compel the valve to approach its seat slowly under the influence of the water-pressure behind the valve and the expansive force of the helical spring H, inclosing the stem and abutting against the piston F' at one end and the diaphragm C'' at the other. The outer end of the plug G is recessed to form a stuffing-box G'', closed by a gland G'', through which the end of the stem passes.

The valve is operated by pressure applied to the head or button F' on the protruding end of the valve-stem with sufficient force to over-

come the resistance of the spring H and the water-pressure behind the valve. When thus thrust from its seat, water enters past the valve to the interior of the casing and escapes 5 through the opening c into the interior of the shell and thence through the tube B² and nipple A' to the bowl and is distributed, as usual, to perform the flushing operation. As soon as the hand is removed from the head F³ the 10 valve tends to reseat itself, but is compelled to approach its seat slowly by reason of the dash-pot G', which determines the period of closing. The cone F² on the valve-stem by gradually reducing the effective area of the 15 valve-opening serves to prevent hammering or chattering of the valve on its seat in the act of closing. The opening c is shown in Fig. 3 as delivering the water upward against the interior of the shell; but the opening may be 20 otherwise located, as design or chance may determine, the position of the opening relatively to the passage to the bowl being unimportant excepting as it permits the flow to the bowl to be more or less direct, and thus offers a means 25 of regulating the velocity of the flow through the nipple A'. If the water-pressure be high, the velocity will be lessened by locating the opening as shown in Fig. 3 and compelling the water escaping therefrom to reverse its 30 direction in entering the nipple, or, if the pressure be low, it may be permitted to flow directly from a low point and be therefore less retarded.

In the modification shown in Figs. 4 and 5 35 the shell is formed in one with the bowl by producing in place of the nipple A' a hollow lug A², having oppositely-located openings in which the casing C is received and held by gaskets E² E³, lying between the flanges C' and 40 D' and the front and rear faces of the lug. This form of the invention is preferable, for the reason that the separate casting or shell is dispensed with and also on account of the improved appearance of the bowl. The form 45 shown in the earlier figures is adapted to serve with bowls of the usual construction, while the modified form requires a specially-made bowl; but it will be noted that the valve-casing and its operating means are entirely independent of the shell and may be used without change with either form.

The disposition of the parts comprising the valve and its closing means within the casing permits a very compact structure easily applied, and by means of the soft-rubber gaskets the joints between the shell and casing 55 may be made proof against leakage without danger of fracturing the fragile material of the bowl.

60 The thrust in opening the valve is directly in line with the attachment to the water-service pipe, which, if properly secured, will aid in receiving the strains, and thus relieve the earthenware and reduce the danger of fracture.

It will also be observed that by arranging the valve to open against the water-pressure the interior of the casing is relieved from such pressure when the valve is closed, and if the orifice c be at a low point all the water in the 70 casing may escape to the bowl, thus avoiding submergence of the spring and other internal parts, and consequently lessening deterioration by corrosion and increasing the life of the parts inclosed. To insure such drainage, I 75 prefer to provide a series of small holes c', arranged annularly of the casing on the line of the orifice c. Thus conditioned one or more of the holes c' will always lie in the lowest portion of the casing and permit the slow escape of water without materially affecting the main discharge through the orifice c.

I claim—

1. A valve-casing having a water-inlet at one end and a valve-operating means at the 85 other end, a valve within said casing, a thimble on said inlet end having a flange, and a flange on the opposite end of said casing, in combination with a shell receiving said casing and holding the latter by the engagement of 90 said flanges with said shell and having a downwardly-projecting bell and tube extending within the same, and a discharge-opening in said casing within said shell.

2. The valve-casing C having a discharge-opening c therein, a flange C' on one end of said casing, the thimble D on the opposite end having a flange D' thereon, the valve F in said casing and means for operating it, in combination with a shell of larger diameter than said 100 casing, in which the latter is received and held by the engagement of said shell between said flanges, and a passage from said shell to a bowl, whereby water entering said casing through said thimble will be discharged through said 105 opening to the interior of said shell and thence through said passage to said bowl, said shell having a depending bell adapted to loosely inclose the nipple of the bowl, and a tube mounted concentrically in said bell and extending 110 loosely within said nipple.

3. The valve-casing C having a discharge-opening c therein, a flange C' on one end of said casing, the inlet-thimble D on the opposite end having the flange D', the diaphragm C² 115 and valve-seat C³ in said casing, the valve F matching to said seat and arranged to open against the pressure of water entering said thimble, the valve-stem F' extending axially of said casing, the cup-leather piston F⁴ on 120 said stem, the plug G serving to close the outer end of said casing and also as a cylinder for said piston, a spring H between the latter and said diaphragm and aiding the water-pressure in urging said valve to its seat, 125 all combined and arranged to serve with a shell of greater diameter than said casing, in which said casing is received and held by the engagement of said flanges with the opposite faces of said shell and said shell formed with a 130

depending bell portion and a detachable tube disposed concentrically thereof and adapted to extend within the nipple of the bowl.

4. The cylindrical valve-casing C having a diaphragm C² and valve-seat C³ therein, a valve F on the pressure side of said diaphragm, a valve-stem extending axially through said casing from said valve and serving as a means for forcing said valve from its seat, a cup-leather piston F⁴ on said stem, and a cylinder G' therefor, a spring H between said diaphragm and piston tending to close said valve, and a conical swell on said stem adjacent to said valve and serving gradually to close the opening in said valve-seat as the valve approaches the latter in the act of closing, the flange C' on said casing, the thimble D on the inlet end thereof having the flange D', and a shell of larger diameter than said casing, serving to receive said casing and hold it by being engaged between said flanges, and a discharge-opening in said casing within said shell.
5. The valve-casing C having a discharge-opening c' therein and a series of smaller holes c', a flange C' on one end of said casing, the

inlet-thimble D on the opposite end having the flange D', the valve F in said casing and means for operating it, in combination with a shell of larger diameter than said casing, in 30 which the latter is received and held by the engagement of said shell between said flanges, and a passage from said shell to a bowl, whereby water entering said casing through said thimble will be discharged through said discharge-opening to the interior of said shell and thence through said passage to said bowl, and any water not discharged through said opening will escape through said holes, said shell being formed with a downwardly-projecting bell and a tube concentrically mounted within said bell and detachably secured to the upper portion thereof and adapted to extend loosely within the nipple of a bowl.

In testimony that I claim the invention 45 above set forth I affix my signature in presence of two witnesses.

ROBERT F. GILLIN.
